UNITED STATES PATENT OFFICE

WILLIAM H. SOMMER, OF PEORIA, ILLINOIS

BARB WIRE MACHINE

Application filed November 4, 1929. Serial No. 404,763.

This invention has reference to barb wire machines and it has for its principal object to provide such a machine with means for feeding the wire to which the barbs are attached, continuously, and also to provide for wrapping the completed barbed wire on reels or spools at a speed comparatively uniform to the speed with which the wire is continuously fed into the machine.

10 The invention has for a further object to provide in a barb wire machine means for feeding the wire to which the barbs are attached, continuously, and means for retaining the successive barbs as they are wrapped or coiled about the barbed wire in certain uniform and predetermined positions and means for spacing and retaining the barbs attached to the barb wire at equidistant points therealong, whereby in the finished barbed wire 20 the said barbs are uniformly and equidistantly spaced.

25 The invention has for a further object to provide in a barb wire machine means for continuously feeding a pair of spaced longitudinal wires to one of which a barb feed wire is intermittently fed and from which portions thereof are coiled about one of said longitudinal wires and such portions severed to form barbed wires; means being provided 30 to sever such attached barbs; other means being provided to retain the completed barbs in certain predetermined positions while other means are employed to successively receive the attached barbs and retain the same 35 in predetermined equidistant positions on such longitudinal wire and subsequently on the two longitudinal wires twisted to form the completed barbed wire with means to wrap the completed barbed wire on suitable spools 40 or reels.

45 A further object of the invention is to provide in a barb wire machine means for feeding the longitudinal wires horizontally and during such feeding to intermittently attach to one of such longitudinal wires barbs and subsequently to the forming of such barbs to retain them in certain predetermined and equidistant positions on such wires and then to direct the travel of the completed barbed 50 wire in a vertical plane and to wrap such

completed barbed wire on suitable spools or reels, means being provided in the vertical plane of travel of the completed barbed wire to feed such completed barbed wire uniformly onto the spools or reels receiving the same; 55 and in the provision of a housing completely enclosing the spool or reel holding and revolving means and the barbed wire shifting means for uniformly wrapping the said completed barbed wire on such spools or reels. 60

The machine of the invention comprehends in its structure a reciprocating carriage supporting the spindle for wrapping or coiling the barbs and the means for feeding the wire from which the barbs are formed and severed 65 and the severing means, whereby to accommodate the continuous infeeding of the wire to which the barbs are attached and also of the wire to be twisted therewith in the completion of the barbed wire; also an improved 70 spooling means to which may be easily and quickly attached and removed the spools or reels on which the completed barbed wire is wrapped or wound; also improved means for spreading the completed barbed wire uniformly on the spools or reels; also a brake 75 means for bringing to a stop the spooling means when the power is shut off from the machine and other brake means to cooperate with the longitudinal wire feeding means, 80 whereby to insure a wrapping of the completed barbed wire uniformly with the infeeding of the longitudinal wires to which the barbs are attached, and other and additional 85 improvements which will hereinafter more fully appear.

That the invention may be more fully understood reference is had to the accompanying drawings forming part of this description and which disclose a preferred embodiment of the machine in which:—

Figure 1 is a plan view on a greatly reduced scale showing barb wire machine embodying my invention;

Figure 2 is an elevation of one side of the 95 machine;

Figure 3 is a vertical sectional elevation through the machine as the same would appear if taken on the line 3—3, Fig. 1;

Figure 4 is a vertical sectional elevation 100

as the same would appear if taken on the line 4—4, Fig. 1, being transversely to the sectional view of Fig. 3;

Figure 5 is a plan view somewhat enlarged 5 of parts which are shown in plan in Fig. 1, including the reciprocating carriage and parts carried thereby;

Figure 6 is a vertical sectional view as the 10 same would appear on the line 6—6 of Fig. 5;

Figure 7 is a detail elevation of which 15 parts are shown in section of the barb coiling means, the means for retaining the completed barbs in certain predetermined positions and the means for retaining the barbs 20 in equidistant positions on the wire to which they are connected;

Figure 8 is a plan view, partly in section, 25 of the parts shown in Fig. 7;

Figure 9 is an elevation of the double 30 sheave wheel shown at Figs. 7 and 8 from which the two longitudinal wires are directed which form the body of the barbed wire and showing the manner of spacing the barbs at 35 equidistant positions and the subsequent twisting together of the longitudinal wires forming the body of the barbed wire;

Figure 10 is a detail showing the starting 40 of the wrapping or coiling of a barb;

Figure 11 is a detail showing the complete 45 formation of a barb just preceding the severing of the formed barb from the barb feeding wire;

Figure 12 is a detail, partly in section, 50 showing the stationary and movable cutter members;

Figure 13 is a detail in perspective, partly 55 in section, of the stationary cutter member;

Figure 14 is a detail, partly broken away, 60 and partly in section, showing the wrapper for supporting the reels or spools on which the barbed wire is wound, the parts being in an open and collapsed position;

Figure 15 is a detail, partly broken away, 65 of the parts shown in Fig. 14, being an elevation as the same would appear looking in at the parts as they appear in Fig. 3 and also Fig. 14, but with the mechanism closed and in a non-collapsed position;

Figure 16 is a detail in cross section as the 70 same would appear on the lines 16—16, Fig. 14, except that the reel or spool supporting parts are in non-collapsed position and a wire spool or reel shown in dotted lines;

Figure 17 is a detail in plan, partly in section, 75 of parts which are included in Fig. 19;

Figure 18 is a detail section in plan as the 80 same would appear if taken on the line 18—18, Fig. 4;

Figure 19 is a detail section in plan as the 85 same would appear if taken on the line 19—19, Fig. 3, and

Figure 20 is a detail elevation of parts appearing in Figs. 3 and 19 and as the same 90 would appear looking on the lines 20—20 of Fig. 19.

Like characters of reference denote corresponding parts throughout the figures.

The frame

The frame of the machine includes a preferably vertically disposed stationary cylindrical member 1 having an opening 2 in its wall which is of suitable height and width to accommodate the placing in the frame and the removal therefrom of the spools or reels on which the completed barbed wire is wound and, also, to permit an operator to have access to the operating parts within this cylinder. The opening 2 is adapted to be closed by a sliding door 3 which is movable circumferentially of the cylinder, see Figs. 2, 3, 4 and 19, and said door is provided with a handhold 4 to permit an operator or an attendant to open and close said door. The cylinder rests on and is secured to a base frame 5 which is provided interiorly and axially with an oil shroud 5' and with a ball bearing 6 in connection with which is journaled certain operative parts to be described.

Resting on and secured to the upper end 90 of the cylinder is a head frame 7 which said frame, as will be seen in Figs. 1, 2 and 3, projects from and is offset to the body of the cylinder and such extension designated 8. From the extension 8 of the head frame projects a bracket 9, see Fig. 1, and the head frame proper is provided with parallel spaced guides 10 on which is reciprocally mounted a carriage 11, cover plates 12 being provided for the guides and complementary thereto to 100 contain and guide the carriage 11 for sliding movement on the head frame.

While the carriage 11 is not per se a distinctive and component part of the frame structure of the machine, it is a supporting 105 part thereof for certain operating parts, to be described, which due to the continuous in-feeding of the wires, should have reciprocal movement on the machine, whereby to properly apply the barbs to such continuous in-feeding of the wires.

Power and power transmission means

The machine is designed to support its power unit and this would take the form of preferably an electric motor A adapted to be supported by and beneath the extension 8 of the head frame 7, see Figs. 1, 2 and 3, and the motor shaft a is provided with a sprocket pinion b connected by a link belt c with a driving sprocket 13 associated with a clutch member 14, both of which are loosely carried on a main driving shaft 15 journaled in suitable bearings on the head frame of the machine. Cooperating with the loose clutch part 14 is a clutch part 16 having spline and groove connection, not shown, with the main drive shaft 15 and said clutch part 16 has operatively connected therewith a clutch lever 17 pivotally connected 125 to

at 18 to the bracket 9 and to the opposite end of the clutch lever 17 is operatively connected an operator's rod 19 which lies along one side of the machine and guided in a supporting bearing 20. An operator grasping the rod 19 may move it back and forth for the purpose of shifting the clutch part 16, whereby to connect the main drive shaft 15 in driving relation with the motor A and to disconnect it therefrom.

To the main drive shaft 15 is secured a large spiral gear wheel 21, shown in dotted lines in Fig. 1 and in full lines in Fig. 4; a wide faced spur gear wheel 22 shown in dotted lines in Figs. 1, 3, 5 and 6, and a small spiral gear wheel 23 which is shown in dotted lines in Figs. 1, 3 and 5. These gear wheels are spaced from each other throughout the length of the main driving shaft 15, as best seen in Fig. 1.

Referring to the small spiral gear wheel 23, it has a meshing relation with a corresponding spiral gear wheel 24 which is shown in full lines in Figs. 1 and 5 and in full and dotted lines in Fig. 3. This last mentioned spiral gear wheel is secured on a crank shaft 25 which is journaled in suitable bearings secured to the extension 8 of the head frame 7 and to said crank shaft is connected a crank rod 26 and, also, a small gear pinion 27, which is in meshing relation with and adapted to transmit motion to a large gear wheel 28 secured on a driving feed roll shaft 29, see Figs. 1, 2 and 3. To this shaft 29 is, also, secured a sprocket wheel 30 which operates a link belt drive 31 and it in turn transmits motion through a sprocket pinion 32, with which it is connected, to a sheave shaft 33, the latter shaft having a journaled bearing on stationary frame parts, whereby the sheave wheel shaft is immovable in its relation to the slideable carriage 11, supporting parts in association with and adapted to deliver material to a sheave wheel, to be described, on said sheave wheel shaft.

The said shaft 29 has a gear wheel 34 in mesh with a corresponding gear wheel 35 on a driven feed roll shaft 36, see Figs. 1 and 3, and each of said driving and driven feed roll shafts 29 and 36 have spaced pairs of coacting feed rollers 37 and 38, respectively. The function of these pairs or sets of feed rollers 37 and 38 will be described later. They are best seen in Figs. 1 and 3.

The driving feed roll shaft 29 has a fixed position, whereas the driven feed roll shaft 36 is movable, that is to say, the shaft 36, as will be seen from an examination of Figs. 1 and 3, is journaled in a yoke shaped frame 39 pivotally connected to its support at 40 to adapt the feed rollers 38 to be moved toward and from the feed rollers 37 and these sets of feed rollers are yieldingly maintained in a co-operative relation by means of an adjustable spring means 41, see Fig. 3, which is not un-

like that ordinarily employed in machines of this character and for this purpose.

The crank 26 which is connected with the crank shaft 25 has an operative connection at 42 with what may be termed the forward end of the slideable carriage 11, whereby to impart a reciprocating movement forward and backward to said carriage.

On the carriage is journaled in suitable bearings a shaft 43 and to said shaft is secured a large gear wheel 44 which is in meshing relation with the broad or wide faced spur gear wheel 22. It is obvious from this arrangement of the broad faced spur gear wheel 22 and narrow faced spur gear wheel 44 that the latter is adapted to have a movement across the face of the gear wheel 22 during the reciprocation of the carriage 11 while at the same time permitting movement to be transmitted from the gear wheel 22 to the gear wheel 44 and its shaft 43. The said gear wheel 44 has a meshing and driving relation with a small gear pinion 45 connected with a barbed wrapping or coiling spindle 46, see Figs. 1, 5, 7 and 8.

The shaft 43, as will be seen from an examination of Figs. 4 and 5, is provided with a crank portion 47 that is adapted to transmit motion to a rock shaft 48 journaled in suitable bearings on the carriage 11 and to said rock shaft 48 is connected a movable cutter to which further reference will be made.

The gear wheel 44 referred to as being carried on the shaft 43 and receiving its power from the broad faced gear wheel 22 is provided on one side with a spiral gear face 49 with which meshes the teeth of a spiral gear pinion 50 connected with a short vertically disposed feed roll driving shaft 51 journaled in suitable bearings on the carriage 11 and said shaft is provided with a gear wheel 52 meshing with a similar gear wheel 53 carried on a short vertically disposed driven feed roll shaft 54.

The shaft 51 has a substantially fixed position whereas the shaft 54 is capable of movement in relation to the said shaft 51 and the shaft 51 is provided with a feed roll 55 adapted to have a coacting relation with a feed roll 56 on the shaft 54 and the latter shaft is journaled in a pivotally supported frame 57 with which is associated a spring controlled means 58, whereby to yieldingly hold the driving and driven feed rolls 55 and 56 in cooperative relation. The yielding holding means is common in machines of this character. The mechanism last described is best seen in Figs. 1, 4 and 5. The feed rollers 55 and 56 are designed to feed the wire from which the barbs are formed and cut, as will be hereinafter more fully explained, and the sets of feed rollers 37 and 38 are designed for the infeeding of the longitudinal wires constituting the body of the

barbed wire; one set of such rollers adapted for feeding the wire to which the barbs are attached and the other wire to be twisted therewith as the barbs have been attached, whereby to complete the barbed wire.

The large spiral gear 21 to which reference has been made has a meshing and driving relation with a spiral gear wheel 59, see Figs. 3 and 4, which is connected with 10 and forms part of a preferably conical head 60 which is in turn connected with and forms a part of a preferably vertically disposed yoke 61 which has a trunnion or short shaft 62 at its lower end which is journaled and 15 has a bearing relation with the ball bearings 6. Journaled in brackets 63 depending from the conical head 60 is a shaft 64 and on said shaft between said brackets is a cylinder cam 65, while on one end of said shaft is a gear 20 wheel 66 which meshes with a worm 67 on a preferably vertically disposed and inclined shaft 68, the upper end of which is journaled in a bearing 69 on the conical head 60 and its lower end journaled in a bearing 70 is 25 secured to the lower portion of the yoke 61, see Figs. 3 and 4. To the lower end of the shaft 68 is connected a gear wheel 71 meshing with the tooth portion 72 of a disc shaped head 73, forming part of a wrapper, to be 30 described, and also meshing with the tooth portion 72 of said head 73 is a gear pinion 74 carried by a short vertically disposed shaft 75 suitably journaled in bearings attached to the lower portion of the yoke 61 35 and on the lower end of said shaft 75 is a gear wheel 76 in mesh with a gear wheel 77 which is loosely carried on the trunnion or shaft 62 of said yoke 61. Movement is transmitted to the yoke 61 from the main drive 40 shaft 15 through the meshing gears 21 and 59 and as said yoke is revolved the wrapper to which reference has just been casually made rotates therewith and provision is made in the gearing last mentioned to transmit 45 a revolving movement to such wrapper when it is desired to wrap a completed barb wire thereon. In other words the wrapper revolves with the yoke and in addition is adapted to have a revolving movement with- 50 in the yoke. The cylinder cam when rotated is designed to impart movement to parts, to be described, for feeding the completed barb wire uniformly across the face of the wrapper during the revolving movement 55 thereof to wrap the completed barb wire thereon.

I have described the yoke 61 as being provided with a trunnion or short shaft 62 which has a journal bearing in the base 5. At its 60 upper end the conical head 60 of the yoke, which is in axial alignment with the trunnion or shaft 62, has a journal bearing in the head frame 7 in the manner best seen in Figs. 3 and 4 and said conical head at its upper end 65 is in communication with an opening 78

which is provided in a bracket 79 secured to the upper face of the said head frame 7 and in said bracket is journaled the sheave wheel shaft 83 on which is carried a double sheave wheel 80 which has certain structural features 70 and functions in a manner to be described.

Barb coiling means

The coiling spindle for coiling or wrapping the barb has been previously designated as 46, which is continuously revolved, when the machine is in operation, through the meshing of the gears 44 and 45, the latter being connected with said spindle. This coiling spindle is shown in several of the views 75 but its construction and operation will be best understood from Figs. 7, 8, 9 and 10. The coiling end of the spindle is journaled for rotation in a suitable bearing 81 and its opposite end is journaled in a suitable bearing 82 80 and the coiling end of the spindle projects forward of the said bearing 81. This spindle is preferably mounted for rotation so that its axis is in alignment with one of the sets or pairs of feeding rollers 37 and 38 so that 85 the longitudinal strand wire W to which the barbs are attached is fed forward by the said sets or pairs of feed rollers 37 and 38 and thence directed to and through the axially disposed longitudinally opening 83 in the 90 said spindle 46 and in the course of its travel from the feed rollers 37 and 38 to the spindle the strand wire W is directed under the guiding roller 84 and over the guiding roller 85, 95 see Figs. 1, 3, 5 and 6. The roller 84 is journaled on a frame 86 which is pivotally mounted in connection with an oscillatory spindle 87, the function of which is to be further described, and the roller 85 is journaled on 100 a substantially fixed support 88.

The coiling spindle is provided with a reciprocally arranged coiling pin 88' which is suitably offset to its axis and the said coiling pin is adapted when reciprocated in a forward direction to have its end projected without the coiling end of the spindle, whereby to engage with the wire from which the barbs are formed to coil or wrap the end of such wire around the strand wire W. This pin 105 is operatively connected with a sleeve 89 which is slidable on the spindle 46 and the said sleeve is formed or provided with an annular flange 90 having a tapered surface 91 with which is adapted to engage a cam 92 secured to one face of the previously described gear wheel 44. In the operation of the coiling spindle and immediately upon the completion of a barb the coiling pin 88' is retracted and this is accomplished by the cam 92 riding against the flange 90 on the sleeve 110 89 and being connected with the pin 88' retracts the latter as the sleeve 89 is caused to be moved on the coiling spindle. Such movement of the sleeve under the action of the cam 92 is against the tension of a spring 93 115 120 125 130

which, as shown, bears against a shoulder on the said sleeve and against a collar fixed to the coiling spindle and abutting with the bearing member 82. Immediately upon the 5 cam 92 ceasing its action the spring 93 acts to return the sleeve 89 and with it the coiling pin 88' into a protruded position for the purpose of again engaging the wire from which the barbs are formed and coiling such wire 10 in the form of a barb around the strand W.

The bearings 81 and 82 for the coiling spindle are mounted upon and secured to the carriage 11 and it will be obvious, therefore, that as the carriage is reciprocated to and fro or 15 forward and backward that the coiling spindle is likewise reciprocated therewith. This is necessary since the wires to which the barbs are attached are fed continuously into the machine and it is during the forward movement of the carriage and the coiling spindle that the barb is coiled or twisted about the longitudinal wire.

Barb wire feeding and barb severing means

25 The wire from which the barbs are formed and severed is designated W' and is fed intermittently into the machine by means of the pair or set of feed rollers 55 and 56 and is directed to the coiling spindle and across 30 the path of its wrapping or coiling end through a guide 94, see Figs. 5, 6, 8, 12 and 13. The forward end of this guide takes the form of a stationary cutter 95, see Figs. 8, 12 and 13, and coacting with this stationary cutter member is a movable cutter member 96 carried in a chuck 97 connected with the rock shaft 48. This rock shaft is so timed in its movement by the crank shaft 43 as to cause the cutter member 96 to move into relation and to coact with the cutter member 95 to sever therefrom the barb length W' which has been wrapped or coiled about the wire W; such wrapping or coiling having been accomplished by the end of the coiling 45 pin 88 in the spindle 46, across the path of which the end of the wire W' has been projected by the feed rollers 55 and 56.

Barb positioning and retention means

50 I have described the movement of the longitudinal wires to which the barbs are attached as being fed into the machine in a preferably horizontal direction and then being directed vertically to the spools on 55 which the completed barb wire is wrapped. The double sheave wheel 80 over which the longitudinal wires are directed from horizontal to vertical position is rotatable on the sheave shaft 33 which is supported horizontally and located a predetermined distance in advance of the wrapping or coiling portion of the coiler 46, substantially as shown in the figures and, particularly, in 60 Figs. 5, 6 and 7, and between this double sheave wheel and the end of the coiling spin-

dle is located a guiding and positioning member 98, which takes the form of a plate supported on a standard 99. This plate 98 has a portion which lies next adjacent to the peripheral portion of the sheave wheel 80 70 which divides it into two distinct sheave wheel portions 100 and 101 and that portion of the said plate lying between the sheave wheel and the coiling portion of the coiling stem is disposed slightly at an angle to the axis of the said coiling spindle, as is best seen in Fig. 8. The longitudinal wire W leaving the coiling spindle 46 is directed alongside the guiding and positioning plate 98, as is best seen in Figs. 7 and 8, and thence 75 over the sheave portion 100 of said double sheave wheel 80, and it is the function of said guiding and positioning plate 98 to hold the barbs W' as they are attached to the wire W with the barbed ends of such wrapped or coiled barbs in substantially or approximately vertical positions, as is best seen in Fig. 8, whereby the barbs as they are wrapped or coiled on the longitudinal wire are not permitted to become displaced but each and all 80 assume and maintain substantially the same angular positions with respect to the wire upon which they are wrapped or coiled. If this were not so the barbs being coiled or wrapped around an individual wire during 85 the movement of such wire might follow into or assume different positions thereon; however, it is an object of this invention, as stated, to position the barbs on the longitudinal wire and to retain all of the barbs in substantially the same position with respect to such wire and it is the function of the sheave wheel, as I will now explain, to not only retain the barbs in such position but to 90 retain them equidistantly with respect to each other on the wire around which they are coiled or wrapped and to do this I provide the sheave section 100 of the double sheave wheel with a plurality of notches 102 95 and as the longitudinal wire W is advanced with the barbs coiled or wrapped therearound, the successive barbs will enter the successive 100 slots 102, as shown in Figs. 7 and 8, and be held equidistantly on the wire W in relation to each other until the wire W as it 105 is about to leave the sheave 100 will be joined or wrapped with a second longitudinal wire W'. The longitudinal wire W', together with the wire W and the barbs W' constitute 110 the completed barbed wire.

The wire W' is fed into the machine by one of the sets or pairs of feed rollers 37 and 38 and thence under a guiding roller 84' and over a guiding roller 85' and then through a 115 guide 103, see particularly Fig. 5, and thence over the sheave portion 101 of the double sheave wheel 80 and then immediately wrapped or twisted with the wire W at the point where the two wires W and W' leave 120 the double sheave wheel 80, as is shown in 125 Figs. 5, 6 and 7.

65 130

Figs. 7 and 9. From this point the twisted wires W and W³, together with the barbs W³, which are wrapped or coiled about the wire W, are directed by the wrapper, by means of 5 which the completed barb wire is coiled or wrapped on the spools receiving the same, first being acted upon by means for feeding the completed barb wire uniformly across the face of the spools upon which the barbed 10 wire is wrapped.

One of the advantages possessed by this machine is in the feeding of the strand wires in a horizontal plane and attaching the wire barbs thereto in such plane, then fixing the 15 barbs in a predetermined position by means of the sheave wheel 100 and thence directing the strand wires in a vertical plane, and immediately after these wires leave the double sheave wheel to twist the wires together, 20 holding the wire barbs in their predetermined position, completing the barbed wire, and then wrapping the completed barbed wire on a reel or spool, is, that the barbs are held in position, and the twisting of the 25 strand wires made immediately after the barbs leave the double sheave wheel, so that in thus feeding the strand wires, attaching the barbs and then twisting the strand wires together, there is little, if any, chance of a displacement 30 or misplacing of the barbs in the completed barb wire, so that in the completed barbed wire all the barbs are equidistant throughout the strands.

35 *Spool carrier and wrapper*

Reference has been previously made to the disc shaped head 73 which forms part of the wrapper. This head and its tooth portions 72 are journaled for rotation in the lower portion 40 of the yoke 61, see Figs. 3, 4, 14, 15 and 16, and having a pivotal connection with and outside of said head are a plurality of arms or bars 104 which project axially through the said head 73 and transversely of the yoke 45 whereby to provide a collapsible mandrel within the wrapper proper. This mandrel is provided with an axially disposed spindle or shaft 105, the end of which farthest from the head 73 is threaded as at 106. The head 50 of the wrapper, complementary to the head 73 is indicated as 107 and is normally positioned on the opposite side of the yoke to the position of the head 73, and said head 107 is rotatable loosely on a stub shaft 108 having a bearing in a frame part 109 hingedly connected, as shown in Fig. 15, to the base of the yoke 61. Said stub shaft, as well as the head 55 107, are provided with an axial socket to receive the threaded end of the shaft or spindle 106 and the socket of the stub shaft is threaded so as to receive the threads on the end of 60 said shaft or spindle 106. On the outer end of the stub shaft is a hand wheel 110 by means of which an attendant may rotate the 65 stub shaft to detach it and the head 107 from

the threaded end of the shaft or spindle 106 or to attach the same thereto. This may be understood from an examination of Figs. 3 and 14.

The frame 109 is adapted to be swung inwardly and across the lower end of the yoke 61 whereby to place the head 107 in position to secure the ends of the bars 104, comprising the collapsible mandrel, and also to secure a reel or spool, preferably of wire, which is 70 placed on the mandrel to receive the completed barbed wire, and to secure the ends of the bars 104 in firm and secure position, the head 107 is provided with a plurality of slotted openings 111, see Figs. 3 and 14, 75 into and through which the ends of the bars 104 project; the latter having a tapered formation and wedgelike, see Fig. 3, so that when the head 107 is closed and secured in position the said bars 104 are immovably 80 secured; that is, may not be misplaced but capable of being rotated to impart a like rotation to the spools or reels, whereby to wrap the completed barb wire thereon. To lock the frame 109 in closed position, with 85 the parts secured as shown in Fig. 3, a locking means is provided which comprises a 90 slidable bolt member 112 which is adapted to be inserted into and removed from a keeper 113 on the yoke 61, see Fig. 15. The inner end of the slidable bolt member 112 has connection with a roller 114, movable in a 95 suitably shaped slot 115 provided in a camlike member 116 which is oscillatable on the 100 stub shaft 108 and said camlike member has a hand lever 117 provided with a spring held latch 118 which is adapted to have a locking relation with a part of the frame 109, see Figs. 3 and 15. To release the slidable bolt member 112 from the keeper 113 an attendant 105 will grasp the lever 117 and release the latch 118 permitting him to swing the said lever and cause the roller 114 to traverse the slot 115 which is so disposed as to cause a withdrawal of the slidable bolt member 112 from 110 the keeper 113 when the frame 109 may be swung outwardly and back providing, of course, the wheel 110 has been rotated to release the stub shaft 108 from the threaded end of the spindle or shaft 106. To secure 115 the parts in position from which they may have been released it is only necessary, as will be understood, to swing the frame 109 into closed position and reverse the operation of the lever 117 whereby to cause the slidable bolt member 112 to again enter the keeper 113 and lock the parts in position when the wheel 110 will be revolved to cause a threaded engagement of the stub shaft 108 120 with the shaft or spindle 106, locking the 125 collapsible mandrel in the head 107.

This mandrel to which reference has been made is designed, particularly, for receiving a wire reel or spool which has been designated X and its designs best shown in 130

dotted lines in Fig. 16. Such a reel or spool may be secured to the collapsible mandrel by first removing the head 107, releasing the bars 104 so that they will collapse and permit the slipping thereon of the reel or spool and in like manner such a reel or spool may be removed from the mandrel by releasing the head 107 and moving it to an inoperative position to allow a spool or reel to be removed from the mandrel with the completed barbed wire wrapped thereon. It is, of course, understood when a reel or spool X is placed on the collapsible mandrel that it is capable of being rotated therewith, when 15 rotative movement is imparted to the bars 104, through the medium of the tooth portion 72 on the head 73 and that when the said heads 73 and 107 are in closed position, whereby to constitute the complete wrapper, 20 that such spools or reels are firmly held between the two such heads.

I have previously stated that the gear wheel 77 is loosely carried on the short shaft or trunnion 62 of the yoke 61. This being true and if no provision were made for holding such gear, then when power was transmitted from the shaft 15 through the gear wheels 21 and 59 to the yoke 61 the wrapper would rotate with the yoke but would not at the same 25 time rotate within the yoke, as would be necessary to insure the wrapping of the completed barb wire on a spool or spools secured to the wrapper. I have provided that the gear wheel 77 shall be normally held in a fixed 30 position so that as the yoke 61 is rotated the gear wheel 76 will travel around the gear wheel 77, the latter functioning substantially as a rack, whereby movement may be imparted through the shaft 75 to the pinion 74 and through it motion imparted to the tooth portion 72 to impart rotative movement to the collapsible mandrel and, also, movement may be imparted through the tooth portion 72 to the gears 71 and thence through the 35 shaft 68 to the means to be described, for evenly and uniformly distributing the completed barb wire on a reel or spool secured to the wrapper. This holding of the gear wheel 77 is accomplished by the provision of 40 a brake drum 119, which is suitably connected with the hub of the gear wheel 77 and coacting with the said brake drum 119 is a brake band 120, see Figs. 3 and 19, one end of which is connected with a clamp 121' fixedly secured at a suitable point to the lower end of 45 the cylindrical member 1 and the opposite end of said brake band is connected with a reciprocally movable rod 121 which extends from within the cylinder to the outside thereof, and to the outer end thereof the said rod has adjustably connected therewith a cam lever 122 which is fulcrumed at 123 to the base frame 5, the free end portion of the said 50 cam lever normally lying in the path of and adapted to be acted upon by the sliding door

3. Having an operative connection with the said cam lever at a point adjacent to where it is connected with the rod 121 is a bell crank lever 124, which latter has a pivotal connection with a bracket 125 secured to the lower portion of the cylindrical member 1. Connecting to and extending upwardly from the said bell crank lever 124 is a rod 126 and the upper end of said rod is connected with a shaft or spindle 87 which, as previously described, has an operative connection with the frame carrying the guide rollers 84, 84' and 85, 85'. This rod 126 is normally sustained in an upward position by means of a spring 127, one end of which is connected with the rod and the other to the frame extension 8 of the head frame 7. The spring acts to lift and hold the rod 126 and through the action of the bell crank lever 124 to apply power to the brake band 120, whereby to hold the gear wheel 77, and allowing the gear wheel 76 to move therearound and the latter to be rotated by reason of its meshing relation with the teeth of the gear wheel 77, as has been explained.

Attention is called to the feeding of the wires W and W³ by the sets of feed rollers 37 and 38, first under the guiding rollers 84, 84', and thence over the guiding rollers 85, 85', if and when unusual tension is applied to the barbed wire as it is reeled up by the wrapper, the guiding roller 84 and its frame 86 are lifted against the tension of the spring 127 which will force the rod 126 downwardly and release the brake band 120 and, also, release the gear wheel 77 and permit it to run loose and thereafter and during the rotation of the yoke no rotative movement is imparted to the wrapper within the yoke as it rotates with the yoke and then immediately when 100 said tension in the completed barb wire is relieved, the spring 127 immediately acts to again lift the rod 126 to actuate the brake band 120 and hold the gear wheel 77 in a fixed position.

I have described the strand wires W and W³ being fed by the sets of feed rollers 37 and 38 and directed the respective wires first under the guiding rollers 84, 84', and thence over the guiding rollers 85, 85'. If and during the wrapping of the completed barbed wire there should be an unusual tension on the wires W and W³ and if the wrapping is not uniformly with the feeding of such wires by the rollers 37 and 38, the frame 86 will be 120 lifted against the tension of the spring 127, which, through the connections described, will force the rod 126 downwardly and release the brake band 120, and also release the gear wheel 77 and allow it to run loose 125 and thereafter and during the rotation of the yoke 61, no rotative movement is imparted to the wrapper within the yoke, as it rotates with the yoke, then immediately when said tension of these wires is relieved, the 130

spring 127 immediately acts to lift the rod 126 which will result in operating the brake band 120 and retain the gear wheel 77 in a fixed position.

5 Assuming that the attendant desires to remove a completed reel of barbed wire and to replace it with an empty reel, it is possible that the wrapper may not have stopped in a position to enable him, after sliding the door 3, to get possession of the hand wheel 110 and if such were the case and the brake band was not released, he would find it difficult to rotate the yoke whereby to permit him to remove the head 107 of the wrapper so as to 15 take off a full reel and replace it with an empty reel and so it is provided that when the attendant slides the door 3 from across the opening 2 that the door will ride under and engage the free end of the cam lever 122 20 which will actuate the bell crank lever 124 and pull the rod 126 downwardly so as to release the brake band and thereby with considerable freedom and ease the attendant may rotate the yoke to a position to make it easy 25 and convenient to move the head 107 so as to enable the removal of a full reel from the wrapper and to replace it with an empty reel. On closing the door the spring 127 will 30 act to restore the parts and to set the brake band for the purposes explained.

Attention is called to a safety measure which is introduced into this machine which is not present, so far as I know, in machines of like character. By the arrangement of the 35 sliding door 3 in the cylindrical frame, it is practically impossible for an operator or an attendant to get his hands caught either in the yoke or the wrapper, or to become snagged when he attempts to inspect either the 40 rolling up of the barbed wire on the wrapper or to get to the wrapper to remove a completed reel and replace the same with an empty reel. On examining Fig. 19 it will be observed that the sliding door may be 45 opened for a very short distance before it comes into contact with the wrapper 122, which contact would stop the rotating of the yoke and the wrapper. However with such a small degree of opening the operator is permitted to look into the cylindrical member 50 to see how the wrapper is operating, if he cares to do so, but if the door 3 is moved sufficiently to come into engagement with the lever 122, such lever will operate, as previously explained, to actuate the brake band 120 and release the gearing which imparts movement to the yoke and the wrapper. Therefore, it will be observed that as a safety measure when the door is opened, the yoke 55 ceases to rotate and the wrapper ceases to rotate with the yoke.

Barb wire feeding and distributing means

Suspended from within the conical head 60 by preferably a pivotal connection on

trunnions 128 and extending down into the body of the yoke is a tubular member 129 from the lower end of which is supported a star guiding wheel 130. The tubular member has connected therewith a roller 131 which 70 rides on the cylindrical cam 65. It is obvious that when the cam 65 is rotated through the gearing which connects it with the shaft 68 that oscillatory motion will be imparted to the tubular member 129 so as to move the star wheel 130 back and forth above the wrapper. The barb wire comprising the strands W and W³ with the barbs W² thereon leaving the double sheave wheel 80 pass down and through the tubular member 129 and 75 thence over the face of the star wheel 130 whereby during a sidewise or reciprocal movement imparted to the latter will feed or uniformly lay the completed barbed wire on a spool carried by the wrapper, on which the completed barbed wire is wrapped. The 80 said tubular member 129 and its star wheel moving on the fulcrum provided by the trunnions 128. It will be understood from the foregoing description that the feeding means just described for the completed barb wire is operative when the wrapper is rotating within the yoke. It being further understood that the yoke is adapted to be rotated carrying the wrapper with it in its orbit and that during such rotative movement of the yoke the said wrapper is adapted to be rotated within the yoke.

Brake mechanism for the yoke and elements carried thereby

In Figs. 3, 4 and 18 I have shown a brake drum 132 which is preferably connected with the yoke 61 just below the conical head and adapted to have a braking action on said 105 brake band, a brake shoe 133 carried by an arm or lever 134 having a pivotal connection 135 within the cylindrical member 1. To the free end of the lever or arm 134 is connected a link 136 which in turn has connection with a lever 137 pivoted at 138 to a bracket 139 secured to the cylindrical member 1 and the free end of said lever 137 is in operative connection with the operator's rod 19. These parts are so arranged that when the operator 115 shifts the rod 119 to declutch the power from the driving shaft 15 that the brake shoe 133 is set against the drum 132 so as to bring to a stop the yoke 61 and the elements carried thereby.

In general

It is believed that the operation of feeding the pair of strand wires W and W³ into the machine, the attaching of the wire barbs to the strand wire W, the positioning of the ends of the barbs, the definite and predetermined location of the wire barbs on the strand W, the twisting of the strands W and W³ immediately after the positioning and location 125 130

of the wire barbs on the strand W, and the wrapping of the completed barb wire on a spool attached to the wrapper and the uniformly feeding of the completed barb wire on 5 such a spool will be understood from the foregoing description with the further detailed description of such operation; also the controlling of the operation of the wrapper and the barb wire feeding means to the spool on 10 the wrapper will be understood without further description, as well as the application of the brake to the yoke carrying the wrapper and feeding means when the operative parts of the machine are declutched from the 15 driving shaft without further detailed description.

While I have elected to show and describe a preferred embodiment of the invention and the component parts making up the same, it 20 is obvious that the structure is capable of many and various mechanical modifications without departing from the spirit and scope of the invention and therefore, do not wish to be limited to the precise details shown, except 25 as defined by the claims appended thereto.

What I claim is:—

1. In a barb-wire machine, in combination, means for feeding a strand wire, means for successively attaching wire-barbs to said 30 strand wire at spaced distances therealong, means to wrap the barbed wire on a spool, and means between the barb attaching means and said wrapping means for positioning the said barbs in predetermined angular and 35 equidistant positions on the strand wire and then securing the same in predetermined equidistant positions from each other.

2. In a barb-wire machine, in combination, means for feeding continuously a strand wire, 40 means for successively attaching wire-barbs to said strand wire at spaced distances therealong, means to wrap the barbed wire on a spool, and means between the barb attaching means and said wrapping means for positioning the said barbs in predetermined angular and equidistant positions on the strand wire and then securing the same in predetermined equidistant positions from each other.

50 3. In a barb-wire machine, in combination, means for feeding a pair of longitudinal wires, means for successively attaching wire-barbs to one of said longitudinal wires at spaced distances therealong, means to twist 55 the two longitudinal wires together, means to wrap the barbed wire on a spool, and means between the twisting means and barb attaching means for positioning the ends of the successive barbs in predetermined and like 60 positions on their longitudinal wire and then locating the successive barbs in predetermined equidistant spaced position before the twisting of the two longitudinal wires.

4. In a barb-wire machine, in combination, 65 means for feeding continuously a pair of

longitudinal wires, means for successively attaching wire-barbs to one of said longitudinal wires at spaced distances therealong, means to twist the two longitudinal wires together, means to wrap the barbed wire on a spool, and means between the twisting means and barb attaching means for positioning the ends of the successive barbs in predetermined and like 70 positions on their longitudinal wire and then locating the successive barbs in predetermined and equidistant spaced positions before the twisting of the two longitudinal wires.

5. In a barb-wire machine, in combination, means for feeding a pair of longitudinal wires, a coiling means operative to attach wire-barbs to one of said longitudinal wires at spaced distances therealong, means to intermittently feed a barb-wire to said coiling means, means to sever coiled barbs from said barb-wire, means to twist the two longitudinal wires together, means to wrap the barbed wire on a spool, and means between the twisting means and barb coiling means for positioning the ends of the successive barbs in 80 predetermined and like positions on their longitudinal wire and then locating the successive barbs in predetermined and equidistant spaced positions before the twisting of the two longitudinal wires.

6. In a barb-wire machine, in combination, means for feeding continuously a pair of longitudinal wires, a coiling means operative to attach wire-barbs to one of said longitudinal wires at spaced distances therealong, 100 means to intermittently feed a barb-wire to said coiling means, means to sever coiled barbs from said barb-wire, means to twist the two longitudinal wires together, means to wrap the barbed wire on a spool, and means between the twisting means and barb coiling means for positioning the ends of the successive barbs in predetermined and like 105 positions on their longitudinal wire and then locating the successive barbs in predetermined and equidistant spaced positions before the twisting of the two longitudinal wires.

7. In a barb-wire machine, in combination, means for feeding continuously a pair of longitudinal wires, a coiling means in association with one of said wires operative to attach wire-barbs thereto at spaced distances therealong, means to intermittently feed a barb-wire to said coiling means, means to sever coiled barbs from said barb-wires, a reciprocal support for said barb-wire feeding and severing means to accommodate such mechanism to the continuous movement of the longitudinal wires, means to twist the two longitudinal wires together, means to wrap the barbed wire on a spool, and means between the twisting means and barb coiling means for positioning the ends of the successive barbs in predetermined and like 115 positions on their longitudinal wire and then locating the successive barbs in predetermined and equidistant spaced positions before the twisting of the two longitudinal wires.

8. In a barb-wire machine, in combination, means for feeding continuously a pair of longitudinal wires, a coiling means in association with one of said wires operative to attach wire-barbs thereto at spaced distances therealong, means to intermittently feed a barb-wire to said coiling means, means to sever coiled barbs from said barb-wires, a reciprocal support for said barb-wire feeding and severing means to accommodate such mechanism to the continuous movement of the longitudinal wires, means to twist the two longitudinal wires together, means to wrap the barbed wire on a spool, and means between the twisting means and barb coiling means for positioning the ends of the successive barbs in predetermined and like 120 positions on their longitudinal wire and then locating the successive barbs in predetermined and equidistant spaced positions before the twisting of the two longitudinal wires.

9. In a barb-wire machine, in combination, means for feeding continuously a pair of longitudinal wires, a coiling means in association with one of said wires operative to attach wire-barbs thereto at spaced distances therealong, means to intermittently feed a barb-wire to said coiling means, means to sever coiled barbs from said barb-wires, a reciprocal support for said barb-wire feeding and severing means to accommodate such mechanism to the continuous movement of the longitudinal wires, means to twist the two longitudinal wires together, means to wrap the barbed wire on a spool, and means between the twisting means and barb coiling means for positioning the ends of the successive barbs in predetermined and like 125 positions on their longitudinal wire and then locating the successive barbs in predetermined and equidistant spaced positions before the twisting of the two longitudinal wires.

sitions on their longitudinal wire and then locating the successive barbs in predetermined spaced positions before the twisting of the two longitudinal wires.

- 5 8. In a barb-wire machine, in combination, means for feeding continuously a pair of longitudinal wires, means for successively attaching wire-barbs to one of said longitudinal wires at spaced distances therealong, 10 means to twist the two longitudinal wires together, means to wrap the barbed wire on a spool, and means actuated by one of said longitudinal wires when such wire is under predetermined tension for controlling the 15 wrapping means whereby said wrapping means will wrap uniformly with the feed of such longitudinal wires.

9. In a barb-wire machine, in combination, means for feeding continuously a pair 20 of longitudinal wires, means for successively attaching wire-barbs to one of said longitudinal wires at spaced distances therealong, means to twist the two longitudinal wires together, means to wrap the barbed wire on a 25 spool, means between the twisting means and barb attaching means for positioning the ends of the successive barbs in predetermined and like positions on their longitudinal wire and then locating the successive barbs in predetermined spaced positions before the twisting 30 of the two longitudinal wires, and means actuated by one of said longitudinal wires when such wire is under predetermined tension for controlling the wrapping means 35 whereby said wrapping means will wrap uniformly with the feed of such longitudinal wire.

10. In a barb-wire machine, in combination, means for feeding a pair of longitudinal 40 wires in a horizontal plane and at a predetermined point directing their travel in a vertical plane, means located at a point in the horizontal travel of such wires for successively applying wire-barbs to one of said 45 wires, means located approximately at the point of turning of the longitudinal wires from the horizontal to vertical travel for positioning the ends of the successive barbs in predetermined and like positions and then 50 locating the successive barbs in predetermined spaced positions on their securing wire, a wrapper for wrapping the completed barbed-wire on a spool, and means in the vertical path of travel of the barbed-wire for 55 feeding such barbed-wire uniformly onto such spool.

11. In a barb-wire machine, in combination, means to feed strand wires, means to 60 successively apply wire-barbs to one of said wires, means to twist said strands together following the application of said barbs, means carried by said twisting means for 65 wrapping the completed barbed-wire on a spooling means, means actuated by a strand 70 wire when a predetermined tension is pres-

ent in said strands for controlling the rotation of the wrapping means, clutch means for controlling the operation of the machine elements, a brake means for the twisting and wrapping means, and means for manually 75 actuating the clutch means and for simultaneously actuating said brake means.

12. In a barb-wire machine, in combination, means to feed strand wires, means to successively apply wire-barbs to one of said 75 wires, means to twist said strands together following the application of said barbs, means carried by said twisting means for wrapping the completed barbed-wire on a 80 spooling means, means also carried by said twisting means for uniformly feeding the barbed-wire to said spooling means, means actuated by a strand wire when a predetermined 85 tension is present in said strands for controlling the rotation of the wrapping means, clutch means for controlling the operation of the machine elements, a brake means for the twisting and wrapping means, and means for manually actuating the clutch means and for simultaneously actuating said 90 brake means.

13. In a barb-wire machine, in combination, a vertically positioned cylindrical member having an opening in its wall, a slidable door to close said opening, a head frame for said member, means supported on said head frame for feeding a pair of strand wires and also for successively applying wire-barbs to one of said strands, guiding means on said head frame at approximately the axis of said cylindrical member for directing the strands downwardly into said member, a yoke rotatable on a vertical axis in said member, a wrapper rotatable on a horizontal axis at the base of said yoke, means in the yoke for twisting the strands together following the application of the wire-barbs, and means in the yoke for uniformly feeding the barbed-wire to said wrapping means.

14. In a barb-wire machine, in combination, a vertically positioned cylindrical member having an opening in its wall, a slidable door to close said opening, a head frame for said member, means supported on said head frame for feeding a pair of strand wires and also for successively applying wire-barbs to one of said strands, means to position the ends of the successive barbs in predetermined and like positions on their strand wire immediately following their application to such wire, guiding means on said head frame at approximately the axis of said cylindrical member for directing the strands downwardly into said member and for locating the successive barbs in predetermined spaced positions before the twisting of said strand wires, a yoke rotatable on a vertical axis in said member, a wrapper rotatable on a horizontal axis at the base of said yoke, means in the yoke for twisting the strands together fol- 110 115 120 125 130

lowing the application of the wire-barbs, and means in the yoke for uniformly feeding the barbed-wire to said wrapping means.

15. In a barb-wire machine, a combined twisting, wrapping and barbed-wire feeding means comprising a rotatable yoke member, a wrapper rotatable with and within said member, means permitting attaching and removing a spool from said wrapper, means to feed a barbed-wire uniformly to such a spool, gearing between the yoke, the wrapper and said feeding means adapted to rotate the wrapper and feeding means simultaneously during the rotation of the yoke, and a brake means controlling the rotation of said wrapper and said feeding means.

16. In a barb-wire machine, a wrapper for supporting a spool comprising a support, a pair of heads in spaced relation, one of such heads mounted for swingable relation with respect to the other head, a collapsible mandrel having a detachable relation with said swingable head, manually operable means for securing and detaching said swingable head to and from said mandrel, means to secure the swingable head in closed position, and means to rotate said wrapper.

17. In a barb-wire machine, in combination, means for feeding a pair of strand wires in a horizontal plane and at a predetermined point directing said strand wires in a vertical plane, means to apply wire barbs to one of said strand wires during their horizontal travel, means at the predetermined point aforesaid to fix the successive barbs in predetermined position on such strand wire, means in the vertical plane of the travel of the strand wires for twisting the strand wires together immediately on the barbs leaving said barbed fixing means.

18. In a barb-wire machine, in combination, a revoluble yoke and wrapper mounted to rotate with the yoke and adapted to be rotated with the yoke, a housing for enclosing said yoke and wrapper and having an opening to allow access to the wrapper and the yoke, a door slideable on the housing to close said opening, gearing means for rotating the yoke and also for rotating the wrapper within the yoke, means for controlling the rotation of said gearing means, and means actuatable by the door after a predetermined movement of the door for actuating said controllable means.

55 WILLIAM H. SOMMER.
